United States Patent Office

Des. 212,301
Patented Sept. 24, 1968

212,301

DISH DRAINER

William D. Taylor, Wooster, Ohio, assignor to Rubbermaid Incorporated, Wooster, Ohio, a corporation of Ohio

Filed Aug. 28, 1967, Ser. No. 8,408

Term of patent 14 years

(Cl. D44—29)

FIG. 1

FIG. 4

FIG. 5

FIG. 1 is a top plan view of a dish drainer embodying my new design.

FIG. 2 is an elevational view of one side thereof.

FIG. 3 is an elevational view of one end thereof.

FIG. 4 is an elevational view of the opposite side from that shown in FIG. 2.

FIG. 5 is an elevational view of the opposite end from that shown in FIG. 3.

I claim:

The ornamental design for a dish drainer, as shown.
